UNITED STATES PATENT OFFICE

ARSÈNE GODIN, OF SPRINGFIELD, MASSACHUSETTS

DESIGN FOR A BARBER'S MIRROR

Application filed December 16, 1931. Serial No. 42,110. Term of patent 7 years.

To all whom it may concern:

Be it known that I, ARSÈNE GODIN, a citizen of the United States of America, residing at Springfield, in the county of Hampden and State of Massachusetts, have invented a new, original, and ornamental Design for a Barber's Mirror, of which the following is a specification reference being had to the accompanying drawing, forming part thereof.

Figure 1 is a front elevation of a barber's mirror, showing my new design; and Figure 2 is an end view thereof.

1 indicates chromium trim.

I claim:

The ornamental design for a barber's mirror, as shown and described.

ARSÈNE GODIN.
